(57) **CLAIM**

The ornamental design for a case for mobile electronic communications device, as shown and described.

DESCRIPTION

FIG. 1 is a top plan view of a first embodiment of a case for mobile electronic communications device showing our new design;

FIG. 2 is a rear elevational view thereof;

FIG. 3 is a right-side elevational view thereof;

FIG. 4 is a left-side elevational view thereof;

FIG. 5 is a bottom plan view thereof;

FIG. 6 is a front elevational view thereof;

FIG. 7 is a front, right-side, and top perspective view thereof;

FIG. 8 is a top plan view of a second embodiment of the case for mobile electronic communications device showing our new design;

FIG. 9 is a rear elevational view thereof;

FIG. 10 is a right-side elevational view thereof;

FIG. 11 is a left-side elevational view thereof;

FIG. 12 is a bottom plan view thereof;

FIG. 13 is a front elevational view thereof; and,

FIG. 14 is a front, right-side, and top perspective view thereof.

The broken lines in the drawing figures illustrate portions of the case for mobile electronic communications device that form no part of the embodiment of the claimed design in which they are shown.
